UNITED STATES PATENT OFFICE.

HERBERT E. FOWLER, OF NEW HAVEN, CONNECTICUT.

DESIGN FOR A BRIDLE-BIT.

SPECIFICATION forming part of Design No. 13,867, dated April 24, 1883.

Application filed March 21, 1883. Term of patent 7 years.

To all whom it may concern:

Be it known that I, HERBERT E. FOWLER, of New Haven, in the county of New Haven, and State of Connecticut, have invented a new Design for a Bridle-Bit; and I do hereby declare the following, when taken in connection with accompanying drawing and the letters of reference marked thereon, to be a full, clear, and exact description of the same, and which said drawing constitutes part of this specification, and represents a face view.

This invention relates to a design for a harness-bit; and it consists in the configuration of the bit, as shown in the accompanying illustration.

The bit consists of a bar with a downward bend, A, at the center, rising therefrom each side so as to form a slightly upward bend, B;

thence downward toward each end, forming a downward bend, C, of greater extent than the central downward bend, A; thence turned upward to form the ends D, to which the rings E are attached.

I claim—

The herein-described design for a bit, consisting of a bar bent to form a downward central curve, A, thence upward and downward each side, forming the upward bends, B, the ends bent upward forming the downward bends, C C, and terminating in the ends D D, as shown.

HERBERT E. FOWLER.
